MOBILE TARGET FOR A GAME INVOLVING SKILL

Lendon E. Jackson, Sepulveda, Calif.
(7055 Lenox Ave., Apt. 342, Van Nuys, Calif. 91405)

Filed Sept. 17, 1973, Ser. No. 397,962

Term of patent 14 years

Int. Cl. D21—01

U.S. Cl. D34—5 PP

FIG. 1 is a perspective view of a mobile target for a game involving skill embodying my new design; the bottom of the square compartments are closed;

FIG. 2 is a side elevational view;

FIG. 3 is a rear elevational view; and

FIG. 4 is a bottom plan view.

I claim:

The ornamental design for a mobile target for a game involving skill, as shown and described.
